(57) CLAIM

The ornamental design for a stylus holder, as shown and described.

DESCRIPTION

FIG. 1 is a perspective view of a stylus holder embodying the new design;

FIG. 2 is another perspective view of the stylus holder;

FIG. 3 is a front view thereof;

FIG. 4 is a back view thereof;

FIG. 5 is a side view thereof;

FIG. 6 is another side view thereof;

FIG. 7 is a top view thereof;

FIG. 8 is a bottom view thereof;

FIG. 9 is a reference view of the stylus holder in use state 1;

FIG. 10 is another reference view of the stylus holder in use state 1;

FIG. 11 is a reference view of the stylus holder in another use state 2;

FIG. 12 is another reference view of the stylus holder in the use state 2; and,

FIG. 13 is yet another reference view of the stylus holder in the use state 2.

In the drawings, the broken lines depict unclaimed subject matter only and form no part of the claimed design.
